US0D1111609S

(12) **United States Design Patent** (10) **Patent No.:** **US D1,111,609 S**
(45) **Date of Patent:** **** Feb. 10, 2026**

(54) **FRAME RACK**

(71) Applicant: **JFXD TRX ACQ LLC**, Delray Beach, FL (US)

(72) Inventor: **William F. Ryczek**, Pomona, CA (US)

(73) Assignee: **JFXD TRX ACQ LLC**, Delray Beach, FL (US)

(**) Term: **15 Years**

(21) Appl. No.: **29/927,612**

(22) Filed: **Feb. 5, 2024**

(51) LOC (15) Cl. **06-04**

(52) U.S. Cl.

USPC **D6/681.1**

(58) **Field of Classification Search**

CLAIM

The ornamental design for a frame rack as shown and described.

DESCRIPTION

FIG. 1 is a front isometric view of the frame rack.

FIG. 2 is a rear isometric view of the frame rack of FIG. 1.

FIG. 3 is a front view of the frame rack of FIG. 1.

FIG. 4 is a back view of the frame rack of FIG. 1.

FIG. 5 is a left side view of the frame rack of FIG. 1.

FIG. 6 is a right side view of the frame rack of FIG. 1.

FIG. 7 is a top view of the frame rack of FIG. 1; and,

FIG. 8 is a bottom view of the frame rack of FIG. 1.

The broken lines show portions of the frame rack which form no part of the claimed design.

1 Claim, 7 Drawing Sheets
